UNITED STATES PATENT OFFICE

TOBIAS YOUNIS, OF CONCHO, ARIZONA.

SECTIONAL SUPPORTING-POLE.

1,138,826.

Specification of Letters Patent. Patented May 11, 1915.

Application filed March 12, 1914. Serial No. 824,248.

To all whom it may concern:

Be it known that I, TOBIAS YOUNIS, a citizen of the United States, residing at Concho, in the county of Apache and State 5 of Arizona, have invented certain new and useful Improvements in Sectional Supporting-Poles, of which the following is a specification, reference being had to the accompanying drawings.

10 This invention relates to new and useful improvements in supporting poles and more particularly to poles of this character which are used as tent or flag poles, the main object of the invention being the provision of 15 a pole of this character which is formed of a plurality of detachable sections, whereby said pole may be readily taken apart to occupy a minimum space, when not in use.

Another object of the present invention is 20 the provision of a pole of this character which will possess advantages in points of efficiency and durability, is inexpensive to manufacture and, at the same time, is simple in construction and operation.

25 With the above and other objects in view, the invention consists in the novel features of construction, combination and arrangement of parts as will be hereinafter referred to and more particularly pointed out in the 30 specification and claims.

In the accompanying drawing forming a part of this application, Figure 1 is a side elevation of a sectional pole constructed in accordance with my invention. Fig. 2 is a 35 similar view, parts being illustrated in detached position, and one of the parts being illustrated in vertical section. Fig. 3 is an end elevation of one of the sections; Fig. 4 is an end elevation of the other section.

40 In the present invention, I have illustrated my improved supporting pole as formed in two sections, detachably connected together in the manner hereinafter described. The sections herein disclosed are 45 generally indicated by the numerals 1 and 2, the section 1 having a binding strip 3 arranged around the end thereof and adapted to be secured to the section in any suitable manner. The section 1 is provided in its 50 end with a longitudinally extending bore 5 and projecting radially from this opening, are the kerfs 4, the purpose of which will be hereinafter more fully set forth. The section 2 which is adapted to be arranged in 55 opposed relation to the section 1 is of substantially the same diameter and secured to

the end thereof, is a circular plate 6 which is to be of the same diameter as the section 2 and is provided upon its periphery with the opposed arms 7, projecting at right angles from the plate and secured in any suitable manner to the sides of said section, thus securely retaining the plate against any lateral movement upon the section. Formed upon the center of the plate, is a sleeve 8, 60 and projecting radially from said sleeve and formed integral with the plate, are the blades 9 which are adapted to be disposed within the kerfs 4 when the two sections of the pole are connected together, thus retaining the same against any lateral movement when in their effective position.

Secured within the sleeve 8, is a rigid rod 10 which projects out beyond the outer edges of the blades 9 and is adapted to be inserted within the bore 5, when the two sections are connected together to assist the blades in retaining the sections against lateral movement. It is to be noted that the rod 10 is of considerably greater length than the blades 85 9, and the bore 5 which receives said rod extends inwardly of the kerfs 4. The rod 6 serves to prevent undue strain and possible distortion of the blades 9 by the pressure of the band 3 against the ends of said blades. 80 When it is desired to connect the sections together, the outer end of the rod 10 being inserted within the bore 5 and the sections being turned, so that the blades 9 will register with the kerfs 4 and be readily inserted 90 therein, thus retaining the sections against any radial or lateral movement, with respect to each other. It will be apparent from the foregoing that my improved supporting pole may be used either for a tent pole, flag 95 pole or the like and can be taken down so as to occupy a minimum space, when not in use. The device, as herein shown and described is extremely simple in construction and can be manufactured at a comparatively 100 small cost.

While I have shown and described the preferred form of my invention, it will be obvious that various changes in the details of construction and in the proportions may 105 be resorted to for successfully carrying my invention into practice, without sacrificing any of the novel features or departing from the scope of the appended claims.

In the foregoing description, it is stated 110 that the device may be used either for a tent pole or a flag pole, but it will be understood

that the same may be readily used upon telephone or telegraph poles, without departing from the construction illustrated.

Having thus described this invention,
5 what I claim is:—

1. The combination of two parts to be connected together, one of said parts being provided in its end with radially extending kerfs and a longitudinal bore of greater 10 depth than said kerfs and with which said kerfs communicate, a cap plate fixed upon the end of the other part and provided at diametrically opposite points with attaching arms, said cap plate being further provided 15 at its center with a socket and blades extending radially from the socket to the outer edge of the plate to be received in the respective kerfs of the first part, a rod engaged in said socket and adapted to extend 20 into said bore when the parts are connected, and a circumscribing band fixed upon the first part and entirely closing the outer ends of said kerfs.

2. The combination of two pole sections

to be connected together, one of said sections being provided in its end face with a plurality of radially extending kerfs and a longitudinal bore with which said kerfs communicate, said bore being of greater depth than the kerfs, a cap plate fixed upon the end of the other pole section and provided with a central longitudinally extending sleeve, a series of radially disposed blades integrally formed upon the sleeve and plate, said blades being adapted to be received in the kerfs of the first pole section, a rod mounted in said sleeve and of greater length than the blades to extend into the bore of the first pole section, and a circumscribing band fixed upon the first pole section and closing the outer ends of said kerfs.

In testimony whereof I hereunto affix my signature in the presence of two witnesses.

TOBIAS YOUNIS.
